UNITED STATES PATENT OFFICE.

FRANK A. ROBINSON, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,102,688.

Specification of Letters Patent.

Patented July 7, 1914.

Application filed May 28, 1912. Serial No. 700,144.

To all whom it may concern:

Be it known that I, FRANK A. ROBINSON, a citizen of the United States, residing in the borough of Brooklyn, city of New York, 5 in the county of Kings and State of New York, have invented certain new and useful Improvements in Type-Writing Machines, of which the following is a specification.

My invention relates to typewriting machines, and particularly to improved means 10 for feeding a worksheet around the platen of a typewriting machine.

The invention is herein shown as applied to an Underwood typewriting machine having a revolving platen. As this platen rotates, it carries along with it pins or studs which are so spaced as to register with openings in the worksheet which is to be placed on the platen, said pins being preferably in 15 the form of conical projections of a platen surface extension in the form of a flexible strip or band, one end of which band is attached to the body of the platen. When the worksheet is to be inserted, a free end of this extension is led out along a table, mounted on the frame on which the platen is mounted. In this position, a worksheet may be readily placed upon it. When the platen is then turned in line-spacing direction, it winds up 20 the band on it, thus positively drawing the worksheet along, the outer surface of the band forming part of the platen surface engaged by the work-sheet. The band may be caused to ride out along the table by rotating 25 the platen backward, and when the full length of the band has been thus extended on the table, a stop may be arranged to arrest the platen against further rotation. On the table there may be formed a track with 30 which part of the band engages to hold it down flat on the table to preserve the alinement of the band perpendicular to the axis of the platen. The platen frame may, if desired, comprise the usual paper table and 35 pressure rolls for feeding the paper.

Other features and advantages will hereinafter appear.

In the accompanying drawings, Figure 1 is a plan view of a typewriter carriage showing my invention. Fig. 2 is a side view of the same. Fig. 3 shows a worksheet adapted to be used in connection with my invention. Fig. 4 is a front view of a typewriter carriage on a somewhat larger scale than Fig. 5. Fig. 5 is a perspective view of the table

which guides the extension, and some other parts. Fig. 6 is a plan section of the end of a platen, showing the extension in position. Fig. 7 is a transverse section of the same. Fig. 8 is a detail. Fig. 9 is a perspective view of the platen and extension.

On the frame 1 of an ordinary Underwood typewriting machine is a traveling carriage 2 in which is mounted the usual platen frame 3 comprising ends 4 and 5 connected by a paper table 6 and by a tie rod 7. A platen 8 is journaled in said platen frame on its axle 9, and may be turned therein to feed a worksheet by hand wheel 10 or a line-space lever 11, said line-space lever operating through a slide 12 on a ratchet wheel 13, and the throw of said line-space lever may be adjusted by the lever 14.

The work-sheet 16 comprises perforations 15, and it may be guided onto the body of 75 the platen by laying it on the extension 18 so that its perforations fit over conical pins or studs 17 on said extension. This extension 18 is fast at one end to the platen by screws 19 so that it is drawn along and 80 wound on the platen carrying the work-sheet with it as the platen rotates in line-spacing direction. The strip or band 18 when wound is substantially flush with, and forms part of the platen surface which supports the work-sheet. When unwound this strip is a development of a portion or layer 85 of the platen surface, and constitutes a platen surface extension adapted to receive a work-sheet while flat, and then wind it 90 on the body of the roller platen. The free end of said extension is held in position to have the worksheet placed thereon by means of a table 20, and is held down by an overhanging rail 21 as it slides on said table. 95 Pins 22 on said extension, holding it alined are arranged to travel in a slot 21^a formed by said rail, and an extension 26 of said rail is formed on the platen frame end 4 or 5 so as to closely surround the platen and hold the pins 22 to preserve the alinement of the extension, as said extension is wound or unwound as the platen is rotated. The extension 18 is preferably a thin resilient metal strip.

The table 20 may be cut away to form a slot 23, and the platen may be cut away to form a channel 24 under the extension 18, so that said extension tends to lie smooth. Said cut-away portions will accommodate 110

any ends of pins 17 which may project below said extension.

The length of the free portion of the belt 18 is preferably no greater than the circumference of the platen, and when completely wound thereon, constitutes a temporary girdle therefor, and holds its pins 17 spaced equally around the circumference thereof during subsequent revolutions of the platen, 10 so that the perforations in the work-sheet may register successively with the pins and catch thereon, and a long work-sheet may be fed uniformly and positively around the platen without tearing. After a worksheet 15 has been completely filled out and is removed from the platen, the rotation of the platen is reversed; and when the free end 25 of the extension 18 comes to the point where the rail 21 merges with the rail 26, the resilience of the extension will cause said free 20 end to uncoil, and it will travel out and back along the table 20. This presents the pins 17 in position on the table 20 to have a new worksheet placed thereon.

25 When the free end 25 of the extension has reached its farthest limit, so that the extension 18 extends substantially its whole length on the table 20, the backward rotation of the platen is positively arrested by means 30 of a spring detent 27 arranged to enter an opening 28 in said platen. In the forward rotation of the platen, however, said detent is pushed idly aside by the rotation of the platen. Said detent carries a handle 29 by 35 which it may be moved to inoperative position at will.

The outer edge 30 of the table 20 may be steadied by a bracket 31, and the upturned edge 32 of said table acts as a girder to give 40 the table stiffness. The table may be attached to the end frame by means of a screw 33 and a screw 34.

The platen frame may include the usual envelop guide 40 and the front and rear 45 pressure rolls 37 and 38. The tie rod 7 is cut away at 35 and the paper table 6 is cut away at 39 to permit said pins 17 to pass.

In Fig. 1 a worksheet is shown in dotted line position lying on the platen and the extension 18. Here the worksheet is shown as 50 engaging an extension and pins 17 at each end, as is preferable in very exact work. It will be noted that while the perforations 15 in the worksheet may be utilized in loose 55 leaf ledgers, for example, that they need not be an integral part of the sheet, but may be placed on a part of the sheet which may be later torn off and destroyed, and for this purpose the worksheet may be perforated 60 as at 41.

Variations may be resorted to within the scope of the invention, and portions of the improvements may be used without others.

Having thus described my invention, I 65 claim:

1. In a typewriting machine, the combination with a rotatable platen, of an extension fast to said platen and wound on said platen by rotating the platen in line spacing direction, a table onto which the free end 70 of said extension slides when the platen is reversely rotated, and a detent positively arresting said platen in its reverse rotation.

2. In a typewriting machine, the combination with a rotatable platen, of an extension attached at one end to said platen and forming part of the receiving surface of the platen, said extension arranged to extend substantially around the circumference of the platen, and pins on said extension set at 75 intervals such that when said extension is wound on the platen, said pins are uniformly spaced around its entire circumference.

3. The combination with a revolute 80 platen, of an extension connected at one of its ends to said platen to wrap once only therearound, and form part of the work-sheet holding surface of the platen, and work-carrying devices upon said extension.

4. The combination with a revolute 85 platen, of an extension connected at one of its ends to said platen to wind therearound, work-carrying devices upon said extension, and a table whereon said extension may be 90 extended when unwound from the platen by a reverse rotation of the platen.

5. The combination with a revolute 95 platen, of an extension connected at one of its ends to said platen to wind therearound, work-carrying devices upon said extension, a table whereon said extension may be 100 extended when unwound from the platen by a reverse rotation of the platen, and a guiding device for said extension extending along 105 said table.

6. The combination with a revolute 110 platen, of an extension connected at one of its ends to said platen to wind therearound, work-carrying devices upon said extension, a table whereon said extension may be 115 extended when unwound from the platen by a reverse rotation of the platen, and a guiding device for said extension extending along said table and around said platen.

7. The combination with a revolute 120 platen, of an extension connected at one of its ends to said platen to wind therearound, work-carrying devices upon said extension, a table whereon said extension may be 125 extended when unwound from the platen by a reverse rotation of the platen, a guiding device for said extension extending along said table, and means on said extension to engage said guiding device.

8. The combination with a revolute 130 platen, of an extension connected at one of its ends to said platen to wind therearound, work-carrying devices upon said extension, a table whereon said extension may be 135

- extended when unwound from the platen by a reverse rotation of the platen, and a guiding device for said extension extending along said table and around said platen, said guiding device having a channel extending along said table and around said platen, to guide the free end of the said extension away from the platen when the latter is rotated in reverse direction.
9. The combination with a revoluble platen, of a platen surface extension connected at one of its ends to said platen to wind therearound, work-carrying devices upon said extension, a table extending forward at a tangent from the upper surface of the platen, whereon said extension may be extended when unwound from the platen by a reverse rotation of the platen, a guiding device for said extension extending along said table, and a stop to arrest the backward rotation of the platen when the said extension is extended along said table.
10. The combination with a revoluble platen, of a flexible strip forming a platen surface extension connected at one of its ends to said platen to wind therearound, work-carrying devices upon said strip, a table whereon said strip may be extended when unwound from the platen by a reverse rotation of the platen, a guiding device for said strip extending along said table, and a stop to arrest the backward rotation of the platen when the said strip is extended upon said table, said stop being ineffective to arrest the forward rotation of said platen.
11. The combination with a revoluble platen, of a platen surface extension connected at one of its ends to said platen to wrap once only therearound, and work-carrying devices upon said extension, said extension located to one side of the printing field on the platen.
12. The combination with a revoluble platen, of a platen surface extension connected at one of its ends to said platen to wind therearound, and work-carrying devices upon said extension, said extension being of a length to extend once only around the platen to form a girdle rotatable bodily with the platen and capable of advancing a work-sheet for several successive revolutions of the platen.
13. The combination with a revoluble platen, of a pair of extensions arranged at the ends of the platen, each extension connected at one of its ends to said platen to wind therearound, work-carrying devices upon said extensions, and tables whereon said extensions may be extended when unwound from the platen by a reverse rotation of the platen.
14. The combination with a revoluble platen, of a pair of extensions arranged at the ends of the platen, each extension connected at one of its ends to said platen to
- wind therearound, work-carrying devices upon said extensions, tables whereon said extensions may be extended when unwound from the platen by a reverse rotation of the platen, and guiding devices for said extensions extending along said tables to engage the outer edges of said extensions.
15. The combination with a revoluble platen, of a pair of extensions arranged at the ends of the platen, each extension connected at one of its ends to wind therearound, work-carrying devices upon said extensions, and guiding devices arranged along the outer edges of said extensions and continuing around said platen.
16. The combination with a revoluble platen, of a pair of platen surface extensions arranged at the ends of the platen, each extension connected at one of its ends to said platen to wind therearound, work-carrying devices upon said extensions, and guiding devices arranged to extend along the outer edges of said extensions when the extensions extend away from the platen, said guiding devices continuing around said platen; means being provided on said extensions to engage said guiding devices.
17. The combination with a revoluble platen, of a pair of extensions arranged at the ends of the platen, each extension connected at one of its ends to said platen to wind therearound, work-carrying devices upon said extensions, tables whereon said extensions may be extended when unwound from the platen by a reverse rotation of the platen, and guiding devices for said extensions extending along said tables to engage the outer edges of said extensions; said guiding devices formed with channels extending around said platen and along said tables, to guide the free ends of the extensions away from the platen when the latter is rotated in the reverse direction.
18. The combination with a revoluble platen, of a pair of extensions arranged at the ends of the platen, each extension connected at one of its ends to said platen to wind therearound, and work-carrying devices upon said extensions; each extension being of a length to extend once around the platen and rotatable with the platen when wound therearound, so that the extensions may form girdles capable of coöoperating to advance a work-sheet for several successive revolutions of the platen.
19. In a typewriting machine, the combination with a rotatable platen, of a platen surface extension fast at one end to said platen to wrap once only thereon to make a girdle therefor and rotatable bodily with the platen, and pins on said extension adapted to engage a work-sheet.
20. In a typewriting machine, the combination with a rotatable platen, of a platen surface extension fast at one end to said

platens, to wrap once only thereon to make a girdle therefor, pins on said extension adapted to engage a work-sheet, and a table on which said extension may lie flat to permit 5 a work-sheet to be adjusted on the pins.

21. In a typewriting machine, the combination with a rotatable platen, of a band traveling around said platen as it rotates, work-positioning pins on said band, and 10 pins carried by the band and holding said band alined as it travels.

22. In a typewriting machine, the combination with a rotatable platen, of a frame in which said platen rotates, a table on said 15 frame, a platen surface extension fast to said platen and arranged to lie on said table when extended, and a guide holding said extension alined as it extends on said table and is being drawn onto the platen as the latter 20 rotates.

23. In a typewriting machine, the combination with a rotatable platen, of a platen surface extension fast to said platen, to wind thereon to make a girdle therefor, a 25 plurality of pins on said extension adapted to engage a work-sheet, and means extending around a portion of the platen to hold said extension alined as the platen rotates.

24. A rotatable platen having a core or 30 body, and including a flexible platen-surface section fast at one end to said platen and capable of tangential extension to receive a work-sheet while flat, and free to be wrapped once only around the platen core 35 and to form a part of the surface upon which the work-sheet is wrapped when in operative position on the platen.

25. The combination with a rotatable platen having a core and including a flexible 40 platen-surface section fast at one end to said platen and capable of tangential extension, a support for said section when extended, said section being free to be wrapped once 45 only around the platen, and work-holding devices on said section.

26. The combination with a rotatable platen having a core and including platen-surface sections fast at one end to said platen ends, said sections being of extent to wrap 50 once only around the platen and capable of tangential extension to receive a work-sheet while extended or flat, and a series of work-holding pins on each section, the pins of the two series being in register to permit a 55 work-sheet provided with corresponding perforations to be placed at different positions along said sections.

27. A rotatable platen including flexible platen-surface sections connected at one end 60 to the platen and capable of tangential extension, and free to be wrapped once only around the body of the platen, said sections each provided with a row of equally spaced pins, the pins of the two rows being in register to permit a work-sheet provided with 65

corresponding perforations to be placed in different positions along said sections.

28. The combination with a rotatable platen, of supporting tables adjacent the ends of the platen and extending at a tangent therefrom, said platen having surface sections in the form of flexible strips each attached at one end to the platen and extending outward therefrom over said tables, said strips free to be wrapped once only 70 around the platen body to form portions of the platen, and a row of work-holding pins connected to each strip. 75

29. The combination with a rotatable platen, of supporting tables adjacent the ends of the platen and extending at a tangent therefrom, said platen having surface sections in the form of flexible strips each attached at one end to the platen and extending outward therefrom over said tables, 80 said strips free to be wrapped around the platen body to form portions of the platen, and a row of work-holding pins connected to each strip, said tables formed with recesses 85 or slots beneath the pins, and the platen formed with annular recesses beneath said pins when the said strips are wrapped. 90

30. In a typewriting machine, the combination with a rotatable platen, of a flexible platen surface extension fast at one end 95 to said platen and whose extent permits it to wrap once only around the platen to form a temporary platen, and pins on said extension forming a circular row when wrapped around the platen and arranged to 100 successively register with perforations on a work-sheet.

31. A revoluble platen provided with an extension fast at one end thereto and forming a girdle having work-carrying devices 105 thereon, to advance a work-sheet during consecutive revolutions of the platen; said extension constructed to be extended away from the platen and to be entirely wrapped once only around the platen. 110

32. A revoluble platen provided with an extension fast at one end thereto and forming a girdle having work-carrying devices thereon, to advance a work-sheet during consecutive revolutions of the platen; said extension constructed to be extended away from the platen and free to be wrapped once only around the platen and rotated bodily therewith, and a support for the extension when in extended position. 115 120

33. The combination with a revoluble platen having annular recesses adjacent its ends, of strips fast at one end to said platen to wrap once only around the platen and over said recesses to constitute a portion of 125 the platen surface, and having work-carrying studs or devices thereon; means being provided to cause the strips to travel in unison with the platen.

34. The combination with a revoluble 130

platen, of a pair of flexible extensions arranged at the ends of the platen, each extension connected at one of its ends to said platen to wrap once only therearound, and free to rotate with the platen as a surface portion thereof after being wrapped therearound, and work-carrying devices upon said extensions.

35. The combination with a revoluble platen, of a pair of extensions arranged at the ends of the platen, each extension connected at one of its ends to said platen to wrap once only therearound, and free to rotate with the platen after being wrapped therearound, and work-carrying devices upon said extensions, said extensions being arranged so that they constitute a portion

of the platen surface with the printing field of the platen extending between them.

36. A revoluble platen provided with 20 platen-girdling extensions fast at one end thereto and capable of wrapping once only around the platen and having work-carrying devices thereon to coöperate to advance a work-sheet during consecutive revolutions 25 of the platen; said extensions constructed to be extended away from the platen to receive the work, and supports for said extensions extending lengthwise thereof when the extensions are extended.

FRANK A. ROBINSON.
